Primary Examiner — Ricky Pham

(74) *Attorney, Agent, or Firm* — Kenneth A. Smith

(57) **CLAIM**

The ornamental design for flippable waffle maker as shown and described.

DESCRIPTION

FIG. 1 is a top, right perspective view of a flippable waffle maker showing our new design;

FIG. 2 is a front view of the flippable waffle maker depicted in FIG. 1;

FIG. 3 is a right, side view of the flippable waffle maker depicted in FIG. 1;

FIG. 4 is a rear view of the flippable waffle maker depicted in FIG. 1;

FIG. 5 is a left, side view of the flippable waffle maker depicted in FIG. 1;

FIG. 6 is a top view of the flippable waffle maker depicted in FIG. 1;

FIG. 7 is a bottom view of the flippable waffle maker depicted in FIG. 1; and,

FIG. 8 is a top, right perspective view of the flippable waffle maker shown in an alternate configuration.

The broken lines in the drawings illustrate portions of the flippable waffle maker that form no part of the claimed design.

1 Claim, 8 Drawing Sheets
